UNITED STATES PATENT OFFICE.

JOSEPH C. GUNDERSON, OF GRAND FORKS, NORTH DAKOTA.

ENVELOPE-DELIVERY DEVICE.

Application filed March 20, 1922. Serial No. 545,927.

To all whom it may concern:

Be it known that I, JOSEPH C. GUNDERSON, a citizen of the United States, residing at Grand Forks, in the county of Grand Forks 5 and State of North Dakota, have invented certain new and useful Improvements in Envelope-Delivery Devices, of which the following is a specification.

My invention relates to envelope delivery devices, and an object is to provide a device which will receive envelopes and stack them in vertical piles as they come from the printing press. While my device is intended particularly for use in connection with envelopes 15 which have just been printed, it will be understood that it may be used in connection with other printed matter.

The full objects and advantages of my invention will appear in connection with the 20 detailed description, and the novel features of my inventive idea will be particularly pointed out in the claims.

In the accompanying drawings which illustrate the application of my invention in 25 one form, Fig. 1 is a top plan view of the device. Fig. 2 is a fragmentary view taken substantially on the line 2—2 of Fig. 1. Fig. 3 is a perspective view showing the device applied to a printing press. Fig. 4 is a view 30 in section on the line 4—4 of Fig. 1. Fig. 5 is a view in central longitudinal section.

In carrying out my invention, I provide a device which is adapted to be attached to a printing press adjacent the position at which 35 the printed envelopes are removed from the platen. Since the device may be applied to customary and well known printing presses, and since such presses constitute no part of my invention, it is not necessary to illustrate 40 and describe the same in detail. Referring to the construction shown in the drawings, the numeral 10 designates a customary oscillating arm of the press, this arm having attached thereto a horizontal rod 12 which 45 carries gripping fingers 14 which serve to remove the printed matter from the platen. My attachment includes a base member or 50 table 16 which is secured to the upper portion of the press. Mounted for reciprocating movement on this table is a pusher 18 which has downward projections 20 which slide in longitudinal grooves 22 in the surface of the table. The table is provided with an opening 24 extending longitudinally along its 55 center and the walls which limit this opening are provided with grooves 26 which

slidably receive a plate 28 carried by the pusher 18 whereby the latter is prevented from lifting off the table. This plate and the projections 20 guide the pusher during 60 its reciprocating movements. A spring tensioned roller 30 is rotatably mounted in side members 32 so as to be located under the rear end of the table 16. A cord 34 winds upon the roller 30 and is intermediately secured to the plate 28 and then extends forwardly, passing over a sheave 36 secured in the forward end of the opening 24 and over sheaves 38 and 40 mounted on a lateral extension 42 secured to the table. The extreme end of the cord 34 is secured to the oscillating arm 10 previously referred to. Positioned below the front or delivery end of the table is a container 44, the front end of which is open and provided with a retaining plate 46 extending 70 upwardly from the bottom of the container and adjustably secured thereto by a bolt 48 which is slidable in a slot 50.

The operation and advantages of my invention will be obvious from the foregoing 75 description. The envelopes when printed are removed one at a time from the platen by the fingers 14 and deposited upon the table 16. This operation is accomplished by rearward movement of the arm 10, and when this arm moves in the opposite direction during its return movement, the cord 34 is pulled 80 against the tension exerted by the roller 30 and the pusher 18 is caused to move forwardly and push the envelope which has just been brought from the platen over into the container 44 so that the printed envelopes are successively stacked therein, as indicated at E in Fig. 5. The plate 46 is adjusted 85 according to the width of the envelopes so that the latter will be stacked in a neatly arranged pile. The spring tensioned roller 30 causes the cord 44 to be partly wound thereon 90 when the arm 10 moves forwardly so that the pusher is returned in the proper position for engagement back of the envelope 95 which has been deposited by the fingers. 100

I claim:

1. In combination with a printing press having mechanism for removing printed envelopes from the platen, a table adapted to be attached to the printing press for receiving the envelopes removed by said mechanism, a pusher slidably mounted on said table, and means for causing said pusher to reciprocate in synchronism with said envelope removing mechanism. 110

2. An envelope delivery device comprising a table adapted to be attached to a printing press, a pusher slidably mounted on said table, a spring tension roller positioned adjacent said table and a cord attached to said pusher, one portion of said cord being adapted for winding on said roller and another portion of said cord being adapted to be secured to a moving part of the press whereby said pusher will be caused to reciprocate over said table.

3. An envelope delivery device comprising a table adapted to be attached to a printing press, a pusher slidably mounted on said table, a spring tensioned roller positioned under the rear end of said table, a cord intermediately attached to said pusher, said cord having its rear portion adapted for winding on said roller and its forward end adapted to be secured to a moving part of said printing press, and a container positioned below the

delivery end of said table and into which the envelopes are dropped to form a stack when moved by said pusher.

4. An envelope delivery device comprising a table adapted to be attached to a printing press, a pusher slidably mounted on said table, means for guiding said pusher, a spring tensioned roller positioned under the rear end of said table, a cord intermediately attached to said pusher, said cord having its rear portion adapted for winding on said roller, sheaves over which said cord is laterally deflected in order that its forward end may be secured to a moving part of said printing press, and a container positioned below the delivery end of said table and into which the envelopes are dropped to form a stack when moved by said pusher.

In testimony whereof I hereunto affix my signature.

JOSEPH C. GUNDERSON.
